UNITED STATES PATENT OFFICE.

JOHN EDWARD CAPS AND JOHN CONRAD CAPS, OF KANSAS CITY,
MISSOURI.

VARIABLE-SPEED GEARING.

SPECIFICATION forming part of Letters Patent No. 790,425, dated May 23, 1905.

Application filed September 5, 1903. Serial No. 172,146.

To all whom it may concern:

Be it known that we, JOHN EDWARD CAPS and JOHN CONRAD CAPS, citizens of the United States, residing at Kansas City, in the county 5 of Jackson and State of Missouri, have invented a new and useful Variable-Speed Gearing, of which the following is a specification.

This invention relates more particularly to improvements in that class of variable-speed 10 gearing wherein a plurality of different size gears are associated with a shaft and with suitable mechanism by which any of said gears can be connected to the shaft to rotate or be rotated by the same.

15 One of the objects of the present invention is to provide novel mechanism of the above character that is very efficient in action and yet comparatively simple in construction, the connecting device between the shaft and 20 gears being so constructed and related to its actuating means that it may be positively thrown out of action and readily moved to proper position with respect to any gear desired.

25 Another extremely-important object is to make the said actuating mechanism for the connecting device very simple in manipulation, so that the gearing is particularly applicable to self-propelled vehicles, though not 30 limited to such use.

The preferred embodiment of the invention is illustrated in the accompanying drawings and described in the following specification. The invention is not limited, however, to the 35 exact structure and arrangement shown, as will be evident by referring to the claims here-to appended.

In the drawings, Figure 1 is a vertical sectional view through the gearing, showing the 40 mechanism for connecting the different gears to the shaft and the actuating means therefor.

Fig. 2 is a horizontal sectional view, on an enlarged scale, through the same. Fig. 3 is a transverse sectional view taken on the line 45 3 3 of Fig. 2. Fig. 4 is a longitudinal sectional view through the driven shaft. Fig. 5 is a cross-sectional view through the same. Fig. 6 is a detail sectional view showing the cam-shaft.

Similar reference-numerals indicate corresponding parts in all the figures of the drawings.

In the embodiment illustrated a casing 7 is employed, in which is journaled an engine or driving shaft 8 and a driven shaft 9, the latter having the portion located within the casing enlarged and hollow, being provided with a longitudinally-disposed bore 10. The hollow shaft is provided in its opposite interior faces with guideways 11, and oppositely-located openings 12, extending through the walls of said shaft, communicate with the guideways, said openings being separated by cross-webs 13. Gear-wheels 14, 14^a, 14^b, and 15 are carried by the engine-shaft 8 and co-act, respectively, with gear-wheels 16, 16^a, 16^b, and 17, loosely journaled on the hollow shaft 9. The gear-wheels 15 and 17 are the reversing-gears, as will be readily understood.

The gear-wheels 16, 16^a, 16^b, and 17 are mounted upon collars 18, which surround the shaft 9, said collars carrying outstanding clutch members in the form of hoods that comprise angularly-disposed sections 19, bolted together, as shown at 20. One of the sections of each hooded clutch member has a portion lying alongside its gear-wheel and fastened thereto by suitable screws 21, the other section having its inner edge spaced from the shaft 9. Other clutch members co-act with the hooded members and comprise semicircular sections 22, having inwardly-extending lugs 23, that engage in the openings 12 of the shaft 9, so that said sections are revoluble with the shaft. These sections are normally drawn toward each other and held out of coacting relation with the hooded members by means of coiled springs 24 or other suitable gears, attached to inwardly-extending projections 25, formed upon the sections 22 and located on opposite sides of the shaft 9. It will thus be evident that under normal conditions the inner clutch members or sections 22 are out of engagement with the hooded members 19, and the gear-wheels 16, 16^a, 16^b, and 17 are thus disconnected from the shaft 9. The following means are therefore employed for connecting said clutch

80 members when it is desired to connect them to the shaft 9. The sections 22 are provided with 75 projections 26, which are received in the openings 12 of the shaft 9, and the sections 22 are held 80 normally drawn toward each other and held 85 out of coacting relation with the hooded members by means of coiled springs 24 or other suitable gears, attached to inwardly-extending 90 projections 25, formed upon the sections 22 and located on opposite sides of the shaft 9. It will thus be evident that under normal 95 conditions the inner clutch members or sections 22 are out of engagement with the hooded members 19, and the gear-wheels 16, 16^a, 16^b, and 17 are thus disconnected from the shaft 9. The following means are therefore employed for connecting said clutch

members, and consequently the gear-wheels, to the shaft. Projecting from one end of the casing and on opposite sides of the shaft 9 are a pair of slide-rods 26, on which are slidably mounted relatively and also simultaneously movable cross-heads 27. These cross-heads are provided with central openings, in which are journaled flanged collars 28, that are in line with the bore 10 of the shaft 9. Stems 29, disposed in substantially parallel relation, are connected, respectively, with the collars, as shown at 30, said stems projecting into the bore of the shaft. An expandable and contractible key is employed, comprising sections 31, formed, respectively, on the inner ends of the stems 29 and constituting enlargements on the same, said key-sections being longitudinally slideable in the guideways 11 and being adapted to aline with the openings 12 and engage the inwardly-extending projections 23 of the clutch-member sections 22. The key-sections have transversely-disposed sockets 32, in which is pivotally mounted a link 33, that thus connects said sections, as illustrated clearly in Figs. 1 and 2. The outer ends of the stems 29 are overlapped and extend across the space between the heads 27, thereby constituting a support for a coiled spring 34, surrounding the same and having its opposite ends bearing against the inner opposing ends of the flanged collars 28. An actuating-lever 35, pivotally supported between its ends, constitutes the means for moving the key longitudinally in the shaft, said lever having its lower end forked and the terminals slotted, as shown at 36, to engage outstanding pins 37, carried by the outer head 27. The upper end of this lever is formed into a suitable handle 38. The outer head 27 is provided with spaced depending ears 39, in which is journaled a cam-shaft 40, having outstanding eccentrically-disposed pins 41. Links 42 each have one end journaled upon one of the pins 41, the other ends of said links being suitably attached to the inner head 27. The cam-shaft also has a crank-arm 43, to which is attached the lower end of a draw-rod 44, having its upper end fastened to a bell-crank latch 45, pivoted to the upper end 50 of the lever. A quadrant-plate 46 is disposed alongside the upper portion of the lever and is provided with a plurality of deep notches 47, between which are located shallow notches 48. A suitable dog 49, carried by the draw-rod 44, is arranged to engage in any of these notches.

The operation of this mechanism may be briefly described as follows: Assuming the key-sections 31 as being drawn toward each other, it will be evident that all the clutch-sections 22 will be out of coacting relation with the hooded members 19, and thus the shaft 9 and gears 16, 16^a, 16^b, and 17 will not be connected. Therefore when the engine 5 is in operation 65 the shaft 9 will be at rest. If, however, the

key is expanded, the outer edges of the sections 31 thereof will pass into the adjacent openings 12 and bearing against the projections 23 of the clutch-sections will force said sections outwardly and into clamping engagement with the coacting hooded member. The result is that the gear carried by said hooded member will be clutched to the shaft 9, and thus said shaft will be rotated from the engine-shaft 8. The movements of the key are accomplished in the following manner: When the latch 45 and handle 38 are grasped and said latch is drawn toward the handle, it will be evident that the cam-shaft 40 will be partially revolved, thus drawing upon the links, and consequently moving the heads 27 toward each other. This will cause the relative movement of the stems 29, the upper moving into the shaft and the lower moving out of the same. This movement by swinging the link 33 will cause the key-sections 31 to move toward each other, consequently contracting the key and disengaging the same from the adjacent clutch. The same movement of the latch 45 causes the disengagement of the dog 49 from the quadrant-arm, and consequently frees the lever 35. The operator, maintaining the grasp upon the latch 45, thereupon swings the lever a sufficient distance to bring the key into coacting relation with the clutch of the desired gear. This relation can be readily ascertained by the position of the dog 49 with respect to the deep notches, said notches corresponding to the number of gear-wheels, as will be evident by the reference-numerals 1, 2, 3, and 4. When this relation has been obtained, it is only necessary to release the latch, whereupon the spring 34, acting against the heads 27, will force said heads apart, returning the cam-shaft to its original position and drawing the dog 49 into the new notch. The separation of the heads also causes a retrograde relative movement on the part of the stems 29, thus swinging the link toward an upright position and expanding the key. Said key will therefore move into coacting relation with the adjacent clutch member, and consequently the gear-wheel desired will be connected to the shaft. If it is desired to disconnect the shaft entirely from all of the gear-wheels, this may be readily accomplished by throwing the dog into one of the shallow notches 48, which will maintain the heads in their nearer relation, and consequently hold the key contracted.

It is desired to call attention to the following advantages which this structure has: In the first place it will be observed that the key is positively contracted, so that it is out of coacting relation with the various elements and it can be held out of said relation during its entire movement from one end of the gearing to the other. The result is that comparatively little power is needed to vary the speed, and said key will not momentarily throw each gear 120 125 130

into action during its longitudinal movement. There is thus a distinct advantage for having mechanism which will positively contract the key and hold it out of coacting relation during its longitudinal movement, though in the construction shown the mechanism for expanding the key is not positive but reactive, said expansion being caused by the spring 34. A further and very important advantage resides in the fact that the entire mechanism is controlled by a single lever and latch, so that it can be readily operated by an inexperienced person, and thus is particularly applicable to self-propelled vehicles, though, as already stated, it is not limited to this use. Moreover, the mechanism by which these various desirable results are obtained is comparatively simple and at the same time practicable in that it is not liable to derangement.

From the foregoing it is thought that the construction, operation, and many advantages of the herein-described invention will be apparent to those skilled in the art without further description, and it will be understood that various changes in the size, shape, proportion, and minor details of construction may be resorted to without departing from the spirit or sacrificing any of the advantages of the invention.

Having thus described our invention, what we claim as new, and desire to secure by Letters Patent, is—

1. In mechanism of the class described, the combination with a shaft, of a plurality of gears mounted thereon, means for connecting the gears to the shaft including key members that are relatively movable longitudinally of the shaft, and means for separating the members upon their said relative longitudinal movements.

2. In mechanism of the class described, the combination with a shaft, of a plurality of gears mounted thereon, means for connecting the gears to the shaft including relatively movable key members that are slideable longitudinally with respect to each other, and means for separating the members upon their relative longitudinal movements.

3. In mechanism of the class described, the combination with a shaft, of a plurality of gears mounted thereon, and means for connecting the gears to the shaft, said means including a key movable on the shaft to coacting relation with the different gears and comprising key-sections that are relatively movable longitudinally of the shaft, and means interposed between the key-sections for causing the separation thereof upon the relative longitudinal movement of said key-sections.

4. In mechanism of the class described, the combination with a shaft, of a plurality of gears mounted thereon, and means for connecting the gears to the shaft, said means including a key movable on the shaft to coacting relation with the different gears and comprising rela-

tively movable key-sections, and a link connecting the key-sections for causing the separation thereof upon their relative movement.

5. In mechanism of the class described, the combination with a hollow shaft, of a plurality of gears mounted thereon, means for connecting the gears to the shaft including relatively movable stems slidably mounted in the shaft and each having a key-section, and means for separating said sections upon the relative movement of the stems.

6. In a machine of the class described, the combination with a hollow shaft, of a plurality of gears mounted thereon, and means for connecting the gears to the shaft, said means including relatively movable stems slidably mounted in the shaft and having key-sections that separate upon the relative movement of the stems, a connection between the stems for effecting the separation thereof, and means for moving the stems simultaneously and relatively.

7. In mechanism of the class described, the combination with a hollow shaft, of gears mounted on the shaft, and means for connecting the gears to the shaft, said means including relatively and simultaneously movable stems located longitudinally within the shaft, key-sections carried by the stems, and a link connecting the key-sections.

8. In mechanism of the class described, the combination with a hollow shaft, of gear-wheels loosely journaled on the shaft and having clutch members, other clutch members revolvable within the shaft and coacting with the clutch members of the gears, stems slidably mounted in the shaft, and relatively movable key-sections carried by the stems and movable toward and away from each other, said key-sections being movable into engagement with the different clutch members of the shaft, and a link connecting the key-sections.

9. In mechanism of the class described, the combination with a shaft, of gears mounted thereon, means for connecting the gears to the shaft, said means including an expansible and contractible key that is slideable with respect to the shaft, means for locking the key against sliding movement and effecting the expansion and contraction thereof, and a device for operating said means to simultaneously unlock and contract the key.

10. In mechanism of the class described, the combination with a shaft, of a plurality of gears mounted thereon, means for connecting the gears to the shaft, said means including an expansible and contractible key that is movable longitudinally of the shaft, and common means for locking the key against its longitudinal movement and effecting the expansion and contraction of the same.

11. In mechanism of the class described, the combination with a shaft, of a plurality of gears mounted thereon, means for connecting the

gears to the shaft, said means including an 5
expansile and contractile key that is movable longitudinally of the shaft, actuating means for effecting the longitudinal movement
of the key, mechanism for contracting the
key, and a lock for the actuating means, said
lock being connected with the contracting
mechanism.

12. In mechanism of the class described, the
10 combination with a shaft, of a plurality of gears
mounted thereon, means for connecting the
gears to the shaft, said means including an
expansile and contractile key that is slide-
15 able with respect to the shaft, means for ex-
panding the key including relatively and si-
multaneously movable heads, means for si-
multaneously moving the heads, and separate
means for relatively moving the heads.

13. In mechanism of the class described, the
20 combination with a shaft, of a plurality of gears
mounted thereon, means for connecting the
gears to the shaft, said means including an
expansile and contractile key that is slide-
25 able with respect to the shaft, means for ex-
panding the key including relatively and si-
multaneously movable heads, means for sim-
ultaneously moving the heads, means for rela-
tively moving the heads, and a lock connected
30 to the relatively moving means for holding
the simultaneously-moving means against ac-
tion.

14. In mechanism of the class described, the
combination with a shaft, of gears mounted
thereon, and means for connecting the shaft
35 and gears, said means including simultane-
ously and relatively movable heads, stems
connected to the heads, key-sections carried
by the stems and coacting with the gears, and
means for relatively and simultaneously mov-
40 ing the heads.

15. In mechanism of the class described, the
combination with a hollow shaft, of gears
mounted thereon, and means for connecting
the shaft and gears, said means including si-
45 multaneously and relatively movable heads,
stems connected respectively to the heads,
key-sections carried by the stems and coact-
ing with the gears, a connection between the
key-sections for separating them upon the
50 relative movements of the heads, and means
for relatively and simultaneously moving the
heads.

16. In mechanism of the class described, the
combination with a shaft, of gears mounted
55 thereon, and means for connecting the shaft
and gears, said means including simultane-
ously and relatively movable heads, stems
connected to the heads, key-sections carried
by the stems and coacting with the gears,
60 means for positively and relatively moving
the heads in one direction, and reactive means
for relatively moving the heads in the oppo-
site direction.

17. In mechanism of the class described, the
65 combination with a hollow shaft, of gears

mounted thereon, relatively movable heads
located at one end of the shaft, stems carried
respectively by the heads and projecting with-
in the shaft, key-sections carried by the stems,
means located between the sections for sepa-
70 rating the same upon the relative movements
of the heads, a spring interposed between the
heads, and a lever connected to one of the
heads.

18. In mechanism of the class described, the
75 combination with a casing, of slide-rods pro-
jecting from one end of the casing, a hollow
shaft journaled in the casing, gears loosely
mounted on the shaft, coacting clutch mem-
80 bers carried respectively by the gears and
shaft, relatively and simultaneously movable
cross-heads slidably mounted on the slide-
rods, stems connected respectively to the
heads and extending into the shaft, key-sec-
85 tions carried by the inner ends of the stems,
a link pivotally connecting the sections, said
key-sections coacting with the clutch mem-
bers, a spring interposed between the heads,
means for relatively moving the heads and an
actuating-lever attached to one of the heads.
90

19. In mechanism of the class described, the
combination with a shaft, of a plurality of gears
mounted thereon, a key movable on the shaft
and into and out of coaction with the gears,
means for moving the key on the shaft and
95 into coacting relation with the gears, and pos-
itive means for moving the key out of such
coaction and holding the same during its move-
ment upon the shaft.

20. In mechanism of the class described, the
100 combination with a shaft, of a plurality of gears
mounted thereon, and means for connecting
the gears to the shaft, said means including
an expansile and contractile key movable
longitudinally of the shaft, means for moving
105 the key longitudinally with respect to the
shaft, and a key-actuated device for positively
contracting said key and holding the same in
contracted condition during its movement.

21. In mechanism of the class described, the
110 combination with a shaft, of a plurality of gears
mounted on the shaft, an expansile and con-
tractile key for connecting the gears to the
shaft, said key being movable longitudinally
of the shaft, manually-operated means for
115 moving the key longitudinally of the shaft,
and manually-operated means for positively
contracting the key and holding the same in
contracted condition during its longitudinal
movement.

22. In mechanism of the class described, the
combination with a shaft, of a plurality of gears
mounted on the shaft, and mechanism for con-
necting the gears to the shaft, said mech-
anism including an expansile and contractile
125 key that is movable longitudinally of the shaft,
means for moving the key longitudinally of
the shaft, means for contracting the key and
holding the same in contracted condition dur-
ing its longitudinal movement, and a lock car-
130

ried by the said contracting means for holding the longitudinally-moving means against movement.

23. In mechanism of the class described, the combination with a shaft, of gears mounted on the shaft, and mechanism for connecting the gears to the shaft, said mechanism including an expandible and contractible key that is movable longitudinally of the shaft, a lever for moving the key, and means carried by the lever and connected with the key for expanding and positively contracting said key.

24. In mechanism of the class described, the combination with a hollow shaft, of gears mounted thereon, and means for connecting the gears to the shaft, said means including an expandible and contractible key that is movable longitudinally of the shaft, a lever for moving the key longitudinally of the shaft, means for expanding and contracting the key, and a locking device mounted on the lever and connected with the expanding and contracting means.

25. In mechanism of the class described, the combination with a hollow shaft, of gears loosely journaled thereon, clutch members fixed to the gears, other clutch members co-acting with the gear-clutch members and carried by the shaft, relatively and slidably mounted heads, stems affixed to the heads and extending within the hollow shaft, key-sections carried by the stems and movable toward and from each other, said key-sections coacting with the clutch members, a link connecting the key-sections, a spring interposed between the heads, a lever having a connection with one of the heads, a cam-shaft journaled on one of said heads, links connecting the cam-shaft and the other head, a quadrant-arm disposed contiguous to the lever, and a lock carried by the lever and coacting with the quadrant-arm, said lock also having a connection with the cam-shaft.

26. In mechanism of the class described, the combination with a hollow shaft having oppositely-disposed openings and an interior guideway, of a plurality of independent gear-wheels journaled on the shaft, a hooded clutch member attached to one side of each wheel, another clutch member located within the hooded member and comprising sections having inwardly-extending lugs located in the openings

in the shaft, springs connecting the sections for moving them toward each other, and an expandible key movably located in the shaft 55 and engaging in the guideway thereof, said key being movable into the openings of the shaft and engaging the lugs of the various clutch - sections to force said sections outwardly.

27. In mechanism of the class described, the combination with a shaft, of transmission means mounted thereon, a key for connecting the shaft to the means, and a device actuated by the movement of the key to effect the engagement and disengagement of said key with and from the transmission means.

28. In mechanism of the class described, the combination with a shaft, of transmission means mounted thereon, a key for connecting 70 the shaft to the means, and a device positively operated in different directions by the key to effect the positive engagement of said key with and the positive disengagement of said key from the transmission means.

29. In mechanism of the class described, the combination with a shaft, of gears mounted thereon, stems movable longitudinally on the shaft to carry them to different gears and having relative movements with respect to each 80 other, said relative movements being also longitudinally of the shaft, means connected to the stems for effecting both of said movements, and means for spreading the inner ends of the stems upon the relative longitudinal 85 movements thereof to effect engagement with the gears.

30. In mechanism of the class described, the combination with driving means, of transmission means, a key carried by one means and 90 movable into and out of engagement with the other, means for locking the key and effecting the disengagement thereof, and a device for operating said locking means to simultaneously unlock and disengage said key.

In testimony that we claim the foregoing as our own we have hereto affixed our signatures in the presence of two witnesses.
